ABSTRACT

A rack constructed from a single blank is folded or bent into a shape to accommodate a plurality of test tubes. The rack may include an elongated light source to backlight a series of test tubes.

FIG. 1.

FIG. 2.

FIG. 3.

FIG. 4.

VIEWING RACK

BACKGROUND OF THE INVENTION

The concept of test tube racks or holders is extremely old. The very nature of the structure of the round bottomed test tube prevents its being able to rest vertically as no base is provided. The round bottom of the test tube is a necessary feature; to accomplish ease of manufacture and to simplify cleaning. Test tube racks are usually constructed in a manner to provide a single row and to eliminate as much as possible obstructions which might obscure view of the test tube from its bottom to near the top portion. In this manner a transparent glass or plastic test tube may be easily viewed without removal from the rack.

More recently, it has been found desirable to include a source of electric light behind the test tubes to provide proper illumination of the contents of the test tube. In this way the test tubes may be adequately back-lighted to provide comparison between the contents of one or more test tubes.

SUMMARY OF THE INVENTION

The present invention is to a rack for holding test tubes and, further, a rack for test tubes having illumination means associated therewith to provide back-lighting of such retained test tubes. The rack is constructed from a single blank of metal or thermoplastic sheet material. By folding or bending the blank it is possible to provide a test tube holding portion, a base portion and a portion designed to provide support to a light source.

THE DRAWINGS

FIG. 1 is a perspective view of the rack of the present invention.

FIG. 2 is a top plan view of the device.

FIG. 3 is a partial front elevation of the device.

FIG. 4 is a cross-sectional view of the device taken along line 4-4 of FIG. 3.

DETAILED DESCRIPTION OF THE INVENTION

Having considered the invention briefly in the above, attention is now directed to the drawings for a more detailed explanation of the invention wherein like reference numerals refer to like parts throughout.

Beginning with FIG. 1, the rack 11 of the present invention is constructed from a single blank 12. The blank 12 may be of sheet metal or thermoplastic material. The material of the blank in any event must be of a material capable of bending to form the final shape. It must also be of sufficient strength and present sufficient rigidity in that it will be self-sustaining while carrying not only a plurality of filled test tubes but also a housing having an electric light source. As the light will preferably constitute a fluorescent type, a conventional ballast will also have to be supported by the rack.

It will be seen that blank 12 receives seven folds, all of which are parallel. The perspective shown by FIG. 1 and the cross-section of FIG. 4 are deemed to present excellent elucidation as to the manner of the bends achieved by the folds. A major portion of the rack 11 is to an inverted V-shaped arrangement, accomplished by a bend 13, thereby producing rearwardly extending leg 14 and a forwardly extending leg 15. The rearwardly extending leg 14 has a relatively small base 16

formed by folding a small portion of leg 14 along bend 17. The base may be folded in either direction.

The forwardly extending leg 15 has a bend 18 to produce another base 19. From FIG. 4 it will be seen that base 16 and base 19 are in the same plane and resulting legs 14 and 15 are approximately the same length. The blank 12 is also bent along line 20 to form an upwardly extending wall 21. It will be appreciated that wall 21 as seen from the embodiment of FIG. 4 presents an angle of slightly greater than 90° with respect to the base. Of course, it is within the purview of the inventive concept to include a 90° angle with respect to the base or even somewhat less.

The upwardly extending wall 21 terminates in a bend 22 to form a small first shelf 23 which extends substantially horizontally. In the embodiment shown by FIG. 4, it will be seen that the first shelf 23 is at a slight downward incline from the bend 22. The shelf 23 terminates in still another bend 24 so that there is another upwardly extending wall 25, approximately parallel with respect to wall 21, that is, may be at a small angle with respect to the vertical. This upwardly extending wall 25 has a plurality of slots 30, as can be readily seen from FIGS. 1 and 3.

The upwardly extending wall 25 terminates in a bend 26. The bend 26 is between a second substantially horizontally disposed shelf 27 which as can be seen from FIG. 4 is slightly downwardly depending. The first shelf 23 and the second shelf 27 are parallel in the present embodiment. Shelf 27 has a series of apertures 28. Each aperture 28 is aligned with respect to a slot 30 located below in the upwardly extending wall 25. As wall 25 is slightly inclined as are the shelves 27 and 23, a test tube 29 may be positioned, or shown in the Figures, through aperture 28 and slot 30 to a position where it is permitted to rest on shelf 23.

In the foregoing, the essence of the rack has been disclosed. To provide a light to illuminate the lower portion of the test tubes 29 a housing 31 containing a fluorescent light is positioned on leg 15 and in the space defined between the leg and that portion of the blank 12 beginning at the bend 18 of the base and that portion then extending upwardly as previously described.

The housing 31 also rests in part on the wall 21. It has a translucent plastic window 32 positioned to provide excellent back-lighting for the test tubes. The housing 31 may have the usual switch means 33 for turning the light on and off. Being a fluorescent lamp conventional ballast may be incorporated in the housing. Of course, unless battery operated, the housing 31 will have a conventional electric power cord 34 terminating in a male electric plug 35.

From the foregoing, only one side of the inverted V-shaped section has the test tube containing portion. It will be appreciated that it is within the framework of the present invention to provide a similar arrangement on the other leg 14 side in place of base 16. The other side would then be a mirror image of that described in the above.

The rack may be conventionally formed by providing a suitably shaped jig or metal bending tools. If thermoplastic is employed, it will be necessary to heat warm the plastic to make the material deformable. The apertures for the test tubes may be cut by stamping means prior to undertaking the bending steps.

We claim:

1. A rack comprising a blank having a plurality of parallel elongated bends, a portion having an inverted V-shaped configuration, said portion including downwardly diverging legs, a horizontally extending base integral by a first of said bends with the end of the forwardly extending one of said legs, a first upwardly extending portion integral by a second of said bends with the opposite end of said base, a first shelf integral by a third of said bends with the top of said first upwardly extending portion extending towards said forwardly extending leg and spaced therefrom, a second upwardly extending portion integral by a fourth of said bends with the other end of said shelf, a second shelf integral by a fifth of said bends with the top of said second upwardly extending portion extending towards the same said leg, said second shelf having an elongated edge portion spaced from said leg, said second shelf having a plurality of openings, said second upwardly extending portion having a plurality of openings corresponding to the openings in said second shelf, each corresponding pair of said openings of said second shelf and said second upwardly extending portion being in substantially

vertical alignment adapted to accommodate a test tube, and said first shelf and second shelf being parallel and displaced horizontally whereby when a test tube is positioned in a corresponding pair of said openings in said rack its top is inclined rearwardly from the vertical.

5 2. The rack of claim 1 wherein the forwardly extending leg, the horizontally extending base, the first and second upwardly extending portion and the first and second shelf define a rectangular elongated space in 10 which said fourth bend and said edge portion of said second shelf are equidistant from said forwardly extending leg.

15 3. The rack of claim 2 wherein an elongated housing is positioned in said space, the housing having a back, a bottom, a front and a top, the housing is supported at its back by said leg and by the first upwardly extending portion at the corner defined by the first and bottom of the housing, the housing having elongated light means, 20 means in the housing to direct the light in the direction of the openings in said upwardly extending portion.
